**SWITCH ACTUATING MECHANISM
FOR CHUTING**

John G. Kay, Detroit, Mich., assignor to F. Jos. Lamb Company, Detroit, Mich., a corporation of Michigan
Filed Jan. 19, 1965, Ser. No. 426,597
11 Claims. (Cl. 200—61.41)

This invention relates to improvements in switch actuating mechanisms, and refers particularly to such mechanisms for attachment to runways such as gravity chuting along which workpieces travel. In automated installations wherein workpieces travel through chuting from one machine to another during the course of their manufacture their movement is usually controlled by electrically operated gates, escapements and the like which are so arranged and timed that a few workpieces rest against the automatic loader for each machine to insure uninterrupted production. However if a breakdown occurs somewhere along the line it is very desirable that the flow of workpieces be promptly halted at some convenient location before they reach the place where the breakdown occurred. For instance should too many workpieces accumulate on gravity chuting against the automatic loader for a machine the excessive pressure exerted by them might have a tendency to jam the loader and render it inoperative.

It is an object of this invention to provide a switch actuating mechanism for attachment to a runway and includes at least one operating rail over which workpieces traveling along the runway must pass, and wherein the rail remains stationary so long as the total weight of workpieces thereon does not exceed a predetermined amount, but when that amount is exceeded the rail is depressed and imparts movement to a switch actuating member; and wherein the switch actuating member and the operating rail return to their normal positions as soon as the weight of workpieces upon the latter drops below the predetermined amount.

Other objects of the invention are to provide such a switch actuating mechanism wherein downward movement of the operating rail or rails is effected by the same weight of workpieces irrespective of their position therewith; wherein provision is made for adjustment of the weight required to cause downward movement of the rails; and which is equally operative irrespective of the direction of flow of workpieces therewith.

Another object of the invention is to provide such a switch actuating mechanism wherein the upper surface of the operating rail or rails is for the major portion of its length at all times parallel with the surface of the runway along which workpieces travel, and wherein under normal operating conditions the rails extend somewhat above the runway and when depressed are in horizontal alignment therewith.

A further object of the invention is to provide such a switch actuating mechanism wherein the opposite extremities of the operating rail or rails are downwardly and outwardly inclined so that they terminate at least flush with or below the surface of the runway at all times thereby permitting easy passage of workpieces at all times between the runway and the rail or rails.

With these and other objects and advantages in view which will become apparent as the description proceeds, the invention is hereinafter described with the aid of the accompanying drawings in which:

FIGURE 1 is a side view of the switch actuating mechanism of the present invention mounted on a known type of gravity chuting with its operating rails in their normal raised position;

2

FIGURES 2 and 3 are views on the lines 2—2 and 3—3, respectively, of FIGURE 1, and

FIGURE 4 is a section on the line 4—4 of FIGURE 1;

5 FIGURE 5 is a side view of a slight modification of the invention wherein only a single operating rail is employed and is shown in its depressed position;

FIGURE 6 is a view on the line 6—6 of FIGURE 5, and

FIGURE 7 is a section on the line 7—7 of FIGURE 5.

10 FIGURE 8 shows another slight modification wherein the switch actuating mechanism is mounted on a curved portion of a runway.

The switch actuating mechanism of the present invention is shown mounted on a runway 1 which includes 15 outer guide rails 2 between which one or more carrier rails 3 of lesser height are provided. All the rails are longitudinally slotted at intervals throughout their length as shown at 4 for the passage of bolts 5 on which spacers 6 are mounted to retain the rails uniformly spaced from one another throughout their length. The spacing between the guide rails 2 is slightly greater than the axial length of workpieces A which are to travel along the surface of the runway formed by the upper edge face or faces of the carrier rail or rails 3.

20 25 7 denotes a supporting plate which in the present instance is secured to the runway by bolts 5a which in addition to passing through slots 4 in the rails 2 and 3 also project outwardly through spacers 8 between the runway and the said plate. Grooved rollers 9 are arranged in opposed pairs and mounted for rotation on bolts 10 which are secured to the plate 7. These rollers act as guides for a slide 11 which is mounted for limited movement in a substantially vertical direction at right angles to the path of travel of workpieces along the runway.

30 35 In FIGURES 1 to 4, inclusive, and FIGURE 6, two operating rails 12 are shown each mounted for substantially vertical movement between one of the guide rails 2 and the carrier rail 3 only one of which is utilized in this case. In FIGURES 5 to 7, inclusive, only a single operating rail 12 is employed which is substantially vertically movable between the two carrier rails 3. Either arrangement may be employed in cases where relatively small cylindrical workpieces of short axial length are to be handled. However for larger or longer workpieces a plurality of operating rails are usually preferred, and when the invention is applied to a runway of the type shown a plurality of carrier rails 3 are also generally preferred. It is of course understood that my invention 40 45 50 may be used on any form of runway which may be vertically apertured or slotted where required for movement of the operating rail or rails therethrough.

55 60 65 The lower portion of the operating rail or rails 12 is secured to the slide 11 by a plurality of bolts 13 which pass through an open-ended slot 14 formed in the underside of the supporting plate 7 intermediately of its width, and have spacers 15 thereon to retain the slide and the operating rail or rails in spaced relation to one another. Some of the bolts 13 are so located relative to the slot 14 that when the slide reaches its upper limit of travel the spacers 15 thereon contact the upper margin of the said slot which then acts as a stop. In the construction shown 70 75 80 in FIGURES 1 to 4 the operating rails 12 are T-shaped in side elevation and have central portions which project downwardly between the bolts 5a on which truncated spacers 6a (FIGURE 1) are provided between the rails 2 and 3. These spacers 6a act as stops beneath the outwardly projecting extremities of the operating rails to limit the downward movement of the rails 12 and that of the slide 11.

In FIGURES 5 to 7, inclusive, the opposite lateral margins of the operating rail 12 are downwardly and inwardly inclined for the major portion of their height, and consequently openings 16 of sufficient vertical length are provided through the operating rail for the passage of the bolts 5a and the spacers 6 thereon since the operating rail is movable substantially vertically while the said bolts and spacers remain stationary. Moreover the openings 16 are preferably so located that the spacers 6 constitute stops to limit the downward movement of the operating rail and the slide 11 secured thereto.

In both embodiments an arm 18 is pivotally mounted at 19 on the supporting plate 7, and extending through an elongated opening 20 formed through the arm adjacent one extremity thereof is a shoulder screw 21 which also passes through the slide 11 and has a nut 22 thereon. This nut is located in a sufficiently large opening 30 (FIGURE 4) formed through the supporting plate 7 to permit pivotal movement of the arm. Means are provided on the opposite extremity of the arm for normally retaining it in such pivotal position that the slide 11 is at its upper extremity of travel. In the present instance a threaded rod 23 projects outwardly from the opposite extremity of the arm and parallel therewith on which at least one internally threaded annular weight 24 is provided so that the position of the latter along the rod may be adjusted according to the weight of workpieces—and thus the number of them—required upon the operating rail or rails 12 to move the latter and the slide 11 to their downward limit of travel and rotate arm 18 about its axis.

The upper surface of the operating rail or rails 12 is at all time parallel with the surface of the runway 1, in this case the upper edge face of the carrier rail or rails 3, throughout the major portion of its length, but at its extremities the upper surface of the operating rail or rails is downwardly and outwardly inclined. When the operating rail or rails are in their normal raised position (FIGURE 1) their intermediate portions are somewhat elevated above the aforesaid surface of the runway and at that time their outer extremities terminate at least flush with or slightly below it to permit easy passage of workpieces onto or from the operating rails; and when the latter are in their downward position (FIGURE 5) their upper surfaces are in horizontal alignment with the surface of the runway and their extremities are below the latter so that workpieces then on the operating rail or rails are still free to continue their travel onto the portion of the runway ahead as soon as there is room thereon to receive them.

Mounted on and in the present instance threaded through the arm 18 is a switch actuating member 25 which is adjustably secured in position by a lock nut 26 to actuate the operating member 27 of a switch 28 mounted in fixed relation to the supporting plate 7 and in the present instance secured thereon. It is understood that the switch is in a circuit including at least one gate, escapement or the like (not shown) which is located upstream of the operating rail and by which the flow of workpieces along the runway is controlled. The switch shown is a conventional micro-switch which is provided with an operating member 27 that includes a push rod normally thrust outwardly by spring action. This type of switch is made in two forms, one with the contacts therein normally open and the other with the contacts normally closed, and wherein that condition is reversed when and only so long as the flush rod is thrust inwardly and retained in that position. Such a switch in one form or the other is frequently utilized in conjunction with my invention because its construction is such that only approximately ten one-thousandths of an inch of movement of the push rod is required to open normally closed contacts or to close normally open ones, and also provision is made therein for overrun of the push rod when moved inwardly. Some of these switches are also made up to

10

include a secondary circuit including a light bulb 29 mounted thereon for giving a visual signal so long as the push rod remains in its inwardly thrust position, at which time in my invention the operating rail or rails are in their downward position and the normal flow of workpieces along the runway is interrupted. As only such slight movement of the operating member 27 is required to actuate the switch the operating rail or rails 12 need only project slightly more than one-sixteenth of an inch above the carrier rail or rails 3 when in normal operating position, which is not sufficient to have any appreciable effects upon the flow of workpieces passing thereover.

FIGURE 8 shows a slight modification wherein the mechanism is to be applied to a curved portion of a runway. In this instance the operating rails 12 are made concentric with the guide and carrier rails 2 and 3, respectively, between which they are mounted for vertical movement. The bolts 5a are held parallel to one another by the use of wedge-shaped washers 5b on their extremities against the inner guide rail 2 to carry the same flat supporting rail 7, and the opposite extremities of the spacers 8 are formed with their opposite end faces not quite parallel to one another if the curvature of the runway is acute.

While in the foregoing the mechanism has been shown in connection with an electric switch, it is of course understood that it is equally applicable in cases where the gate, escapement or the like is operated by fluid pressure in which case it operates a valve mounted in spaced relation thereto.

I claim:

1. In combination a runway along which workpieces are adapted to travel, a switch actuating mechanism comprising a supporting plate attached to the runway, an arm pivoted on the supporting plate, at least one operating rail normally projecting through and only slightly above the surface of the runway along which workpieces are adapted to travel so as to not interfere with the travel of workpieces thereover when in said raised position, means mounted on the supporting plate interposed between the operating rail and the arm whereby movement of either the rail or the arm imparts movement to the other, means connected to the arm for retaining the operating rail in its raised position until a predetermined plurality of workpieces accumulates thereon whereupon said rail is depressed into substantial alignment with the runway, and a switch actuating member associated with the arm for operating a switch mounted in fixed relation to the supporting plate, said interposed means including means whereby the upper surface of the operating rail is maintained at all times parallel throughout the major portion of its length with said surface of the runway.

2. In combination a runway along which workpieces are adapted to travel, a switch actuating mechanism comprising a supporting plate attached to the runway, an arm pivoted on the supporting plate, at least one operating rail normally projecting through and only slightly above the surface of the runway along which workpieces are adapted to travel so as to not interfere with the travel of workpieces thereover when in said raised position, means mounted on the supporting plate interposed between the operating rail and the arm whereby movement of either the rail or the arm imparts movement to the other, means connected to the arm for retaining the operating rail in its raised position until a predetermined plurality of workpieces accumulates thereon whereupon said rail is depressed into substantial alignment with the runway, and a switch actuating member associated with the arm for operating a switch mounted in fixed relation to the supporting plate, both extremities of the upper surface of the operating rail being downwardly and outwardly inclined and terminating at a level below said surface of the runway.

3. In combination a runway along which workpieces are adapted to travel, a switch actuating mechanism comprising a supporting plate attached to the runway, an arm

pivoted on the supporting plate, at least one operating rail normally projecting through and only slightly above the surface of the runway along which workpieces are adapted to travel so as to not interfere with the travel of workpieces thereover when in said raised position, means mounted on the supporting plate interposed between the operating rail and the arm whereby movement of either the rail or the arm imparts movement to the other, means connected to the arm for retaining the operating rail in its raised position until a predetermined plurality of workpieces accumulates thereon whereupon said rail is depressed into substantial alignment with the runway, and a switch actuating member associated with the arm for operating a switch mounted in fixed relation to the supporting plate, the interposed means including a slide mounted for movement on the supporting plate, both the operating rail and the arm being connected thereto.

4. The combination in claim 3, wherein the slide is mounted for straight line movement on the supporting plate, and the operating rail is secured to the slide for movement therewithin and spaced therefrom.

5. In combination a longitudinally curved runway having an apertured surface along which workpieces are adapted to travel, a switch actuating mechanism comprising a supporting plate attached to the runway along the apertured surface thereof, a slide mounted on the supporting plate for substantially vertical movement, at least one operating rail curved concentrically with the runway for vertical movement therethrough, said operating rail being secured to the slide for movement therewith and having its upper surface intermediately of its length parallel at all times with the surface of the runway, an arm pivoted on the supporting plate and connected to the slide, means on the arm adapted to retain the slide and operating rail at their raised positions such that the upper surface of the operating rail projects above the surface of the runway until a predetermined weight load accumulates upon the rail whereupon said rail is depressed into substantial alignment with the runway, means for limiting the travel of the slide, and a switch actuating member associated with the arm for operating a switch mounted in fixed relation to the supporting plate.

6. The combination in claim 5, wherein the opposite extremities of the operating rail are downwardly and outwardly inclined.

7. In combination a runway having an apertured surface along which workpieces are adapted to travel, a switch actuating mechanism including a supporting plate attached to the runway, a slide mounted for substantially vertical movement on the supporting plate, spaced parallel operating rails secured to and spaced from the slide for movement therewith, said rails being adapted to move substantially vertically through the surface of the runway and project above it, the upper surfaces of the operating rails being at all times parallel with the said surface of

the runway intermediately of their length and their outer extremities being downwardly and outwardly inclined, an arm pivoted on the supporting plate and connected to the slide, adjustable means on the arm for retaining the operating rails so positioned that they project above the surface of the runway until a predetermined weight load has accumulated thereon whereupon said rails are depressed into substantial alignment with the surface of the runway, means for limiting the movement of the slide, and a switch actuating member associated with the arm for operating a switch mounted in fixed relation to the supporting plate.

8. In combination, a runway having means defining a workpiece supporting surface, a support mounted on the runway, a slide member guided for rectilinear movement on said support member in a generally vertical path, said workpiece supporting surface of the runway being apertured in a direction longitudinally of the runway, a rail member fixed to said slide member and adapted to project upwardly through the aperture in said supporting surface, means normally biasing the slide member to a position wherein the rail member projects slightly above the workpiece supporting surface of the runway and switch means actuated by the slide member when the latter moves downwardly from the position to which it is normally biased in response to the weight of the workpiece resting on the rail member.

9. The combination called for in claim 8 wherein the rail member extends lengthwise of the runway and has its upper edge extending generally parallel to said supporting surface for a major portion of its length, said upper edge of the rail member tapering into the plane of said supporting surface at the upstream end of the rail member.

10. The combination called for in claim 8 wherein said biasing means includes an arm having a fixed pivotal connection with said support member and a sliding pivotal connection with said slide member spaced lengthwise of the runway from said fixed pivotal connection, said switch means comprising a microswitch having an operating member adapted to be engaged by said arm to actuate the switch means.

11. The combination called for in claim 10 wherein the arm includes a screw adapted to engage the operating member, said screw being adjustable to vary the position of the slide member at which the microswitch is actuated.
